UNITED STATES PATENT OFFICE.

LAWRENCE E. BAUER AND JOHN W. BAUER, OF HAVRE DE GRACE, MARYLAND,
ASSIGNORS TO THE BAUER MANUFACTURING COMPANY, INCORPORATED, A
CORPORATION OF MARYLAND.

CAN-OPENER.

Specification of Letters Patent. Patented Mar. 28, 1916.

1,177,294.

Application filed December 15, 1915. Serial No. 67,043.

To all whom it may concern:

Be it known that we, LAWRENCE E. BAUER and JOHN W. BAUER, citizens of the United States, residing at Havre de Grace, in the county of Harford and State of Maryland, have invented certain new and useful Improvements in Can-Openers, of which the following is a specification.

This invention relates to improvements in can openers, and has for its object to provide a cheap, simple and efficient device for opening the can below the head thereof.

It is the general practice to cut out a portion of the can head, leaving an edge around the opening which forms an obstruction to the contents when being emptied from the can. By our present invention we overcome this objection and dispense with said edge by cutting away the can just below the lower edge of the head, thereby leaving an opening free from any obstruction and coincident with the inner surface of the can.

The invention consists of the novel construction and arrangement of the parts and combinations of parts hereinafter more fully set forth in the following specification and pointed out in detail in the appended claims.

In the accompanying drawings, Figure 1 is a top plan view of our invention showing a can in position for operation. Fig. 2 is a side elevation of Fig. 1. Fig. 3 is a detail plan view of the circular cutting blade. Fig. 4 is a vertical cross-section of Fig. 3.

Referring to the accompanying drawing, forming part of this specification, and in which like reference numerals designate like parts throughout the several views thereof, 1 designates the base to which is bolted an upright 2 the upper end 3 of which extends parallel to and projects over the said base 1. The said upper end is also provided with two integral lugs 4 and 5 projecting from one side thereof each provided with an aperture through which the shaft 6 projects.

The said shaft 6 is provided with a hand wheel 7 on one end and a gear-wheel 8 on the opposite end, and a coiled spring 9 between the lug 4 and the collar 10 which

latter is adjustable on said shaft 6. The coiled spring 9 exerts sufficient tension against the said collar to prevent the head 11 from dropping down when not in use. The said head 11 is provided on its lower surface with a number of tangs 12 which are forced into the head of the can 13 to prevent the latter from turning during the cutting operation. This head 11 is secured to the lower end of the stem 14 which latter projects through an aperture in the upper end 3 of the upright 2 and is provided with a rack 15 which projects through the cut-out 16 and is in mesh with the gear-wheel 8 on the shaft 6, the revolution of which latter causes the stem 14 and consequently the head 11 to be raised or lowered as desired. Revolvably mounted on the stem 14 just above the head 11 is an arm 17 to one end of which is pivoted a lever 18 carrying a circular cutter 19 held to the lower surface thereof by the bolt 20 on which latter it is free to revolve. The said lever 18 is formed with a projection 20 at one side which rests upon the top of the can when the cutting is being done.

The operation of the device is as follows: The head 11 is raised to allow the can 13 to be placed on the base 1 and then lowered by turning the hand wheel 7 until the tangs 12 are forced through the can head. The lever 18 is then drawn toward the can until the cutter 19 is forced through the body of the can just below the head thereof, and by means of said lever 18 the cutter 19 is drawn around the can cutting the head therefrom. The head 11 is then raised from the can by means of the hand wheel 7 and the can is then lifted from the base 1.

Having thus described our invention what we claim is.

1. A can opener comprising an upright having its upper end bent at right angles thereto, a head mounted in the upper end of said upright and adapted to be raised and lowered therein, an arm pivoted to said head, a lever pivoted to said arm, and a revolving cutter pivoted to said lever.

2. A can opener comprising an upright having its upper end bent at right angles, a

head having a stem provided with a rack projecting through said upright, a shaft mounted in the said upright and having a gear-wheel on one end in mesh with said rack to raise and lower said head, and a cutter adapted to be revolved around below said head.

Copies of this patent may be obtained for five cents each, by addressing the "Commissioner of Patents, Washington, D. C."

In testimony whereof we affix our signatures in the presence of two witnesses.

LAWRENCE E. BAUER.
JOHN W. BAUER.
